UNITED STATES PATENT OFFICE.

FRED W. TOBEY, OF GRAND RAPIDS, MICHIGAN.

COMBINED LATCH AND LOCK.

SPECIFICATION forming part of Letters Patent No. 625,217, dated May 16, 1899.

Application filed September 26, 1898. Serial No. 691,912. (No model.)

To all whom it may concern:

Be it known that I, FRED W. TOBEY, a citizen of the United States, residing at Grand Rapids, in the county of Kent and State of Michigan, have invented new and useful Improvements in a Combined Latch and Lock, of which the following is a specification.

This invention relates to certain new and useful improvements in a combined latch and lock; and the invention consists in the combination of parts and details of construction hereinafter described.

The objects of my invention are, first, to form a combined latch and lock for refrigerators and analogous purposes in which the inner face-plate may be attached without the means of screws or bolts; second, in the improved means for moving the locking-dog into a different position either to lock the latch or to unlock it; and, third, in the various combinations of parts hereinafter more fully described, and pointed out in the claims. These objects I accomplish by means of the mechanism illustrated in the accompanying drawings, in which—

Figure 1 is a front elevation of the combined lock and latch constructed in accordance with my invention, showing the latch lowered in position to engage with a suitable catch. Fig. 2 shows a rear elevation of the same, illustrating the covering-plate secured in position without screws or bolts. Fig. 3 shows an edge elevation, illustrating the position of the face-plate and latch. Fig. 4 shows a rear elevation with the face-plate removed, exhibiting the springs, locking device, and latch. Fig. 5 shows a sectional view on line X X of Fig. 2.

Similar letters refer to similar parts throughout the several views.

The lock is provided with a shell or case, preferably of metal, (shown by A.) A thumb-lever turning upon the bolt, shown by B, is provided with a projection J, adapted to engage with the latch C. The latch C turns upon a stud or bolt made integral with the case or shell and is provided with a spring, which spring has its stationary end secured by means of two studs or pins, as shown in Fig. 4, having a free end bearing against the

latch C, adapted to retain the same in the catch, excepting when it is raised from normal position by means of the thumb-lever B.

D is a dog, constructed in the form shown in Fig. 4, turning upon a bolt G and provided with an angular flange E. In the solid lines in Fig. 4 the dog is shown out of position, and in dotted lines it is shown in position to lock the latch in the catch, said dog being provided with a shoulder P, which engages with the latch when said dog is thrown into the position shown by dotted lines in said figure. A spring H has its stationary end held by two studs made integral with the case, as shown in said Fig. 4. The free end of the said spring H is bent at an angle, so as to furnish two flat bearings, which rest against the flat surfaces of the flange E of the dog. In the position shown in the dotted lines the outer or farther surface of the spring H has a bearing against the inner surface of the flange E, thereby holding said dog out of locking position. When the dog is thrown into the position shown by the dotted lines in Fig. 4, the spring H bears against the outer surface of the flange E, said flange E bearing against the second surface of the spring H, said spring thereby holding the dog in locking position until the same shall have been thrown out by means of the key.

The shell or case A is provided with two projections at its front edge, (shown by K and L,) said projections, with the case, forming ways, into which is slid or crowded the face-plate R. M is also a projection from the shell, under which projection is passed the face-plate R and held securely in position. In order to retain the face-plate R securely in position, I provide an opening in the face-plate R, which opening is shown by O. This opening in the face-plate is crowded into position, passes under the projection M, and the projection M may bend downwardly into said opening, thereby securing said face-plate to the shell. By this construction I entirely obviate the necessity of screws or pins in fastening the face-plate to the shell. It will be understood that the shell is made of some material which is somewhat flexible, so that the projection M may readily bend downward

slightly, so as to engage with the hole O in the face-plate R, making a very secure attachment for the face-plate.

The dog D is provided with two projections 5 between which the key passes. The key being turned in one direction throws the dog out of locking position and being turned in the opposite direction throws it into locking position. The dog turns upon a bolt placed 10 at some distance from the keyhole, so as to give a slow motion to the dog. The latch has a portion cut away from beneath, which allows the extended end of the dog to rest beneath the latch, the latch serving the purpose 15 of holding the dog in position and forming a way for the travel of what I term the "locking" end of the dog. The notch P of the dog, however, does not pass beneath the latch, but is of sufficient length to bear upon 20 the upper surface of the latch when the dog is thrown into locking position and to be entirely out of the way of the latch when thrown out of locking position. When the dog is thrown out of locking position, the flange 25 comes in contact with the edge of the case, thereby limiting the throw of the dog in that direction. When thrown into locking position, the end of the dog which passes beneath the latch meets a shoulder on the latch, which 30 limits the throw of the dog in that direction. This is shown by the dotted lines in Fig. 4. The thumb-lever B is placed near the edge of 35 the case, as shown in Fig. 1, being in a convenient position for use and in position to secure the greatest leverage upon the latch.

Having thus described my invention, what I claim to have invented, and desire to secure by Letters Patent, is—

1. In a combined latch and lock, a case pro-

vided at two opposite points with projections 40 to retain the face-plate, and having a flexible projection at a third point adapted to be bent into an opening in the face-plate to retain the latter in place, substantially as described.

2. The combination with a lock-case which 45 is provided with opposite projections, of a face-plate adapted to slide between said projections, and a flexible projection forming part of the case and adapted to be bent into an opening near the edge of the face-plate to 50 prevent the latter from being withdrawn, substantially as described.

3. The combination with a case having two opposite projections, of a face-plate adapted to lie between and be retained by said projections, a third flexible projection forming part of the case, to be bent into an opening near the edge of the face-plate, a latch turning on a fixed pivot and having a free end 55 projecting from the case, a spring to bear on said latch, a dog turning on a pivot between its ends and having a projection to pass beneath the latch and a shoulder to engage the latter when the dog is in locking position, and a spring having two angular portions at different points to engage one or the other of two inclined faces on an angular flange on the dog, whereby the latter is retained in either of its two positions, substantially as 60 described.

In testimony whereof I have hereunto set my hand in presence of two subscribing witnesses.

FRED W. TOBEY.
